UNITED STATES PATENT OFFICE.

OLOF OHLSON, OF NEWTON, MASSACHUSETTS.

SCREW-DRIVER.

SPECIFICATION forming part of Letters Patent No. 761,391, dated May 31, 1904.

Application filed January 4, 1904. Serial No. 187,610. (No. model.)

To all whom it may concern:

Be it known that I, OLOF OHLSON, of Newton, in the county of Middlesex and State of Massachusetts, have invented certain new and useful Improvements in Screw-Drivers, of which the following is a specification.

This invention relates to a screw-driver having a removable shank or screw-engaging portion which is detachably connected with the body or handle portion of the screw-driver and is adapted to be reversed, so that either end may be utilized.

The invention is particularly adapted and intended for screw-drivers of small size, such as are used by watchmakers, although the invention is not necessarily limited to such use.

The invention has for its object to insure a firm connection of the removable shank with the body or holder, so that there will be no possibility of a loose motion of the shank, the construction at the same time being such as to permit the quick and convenient release and attachment of the shank.

The invention consists in the improvements which I will now proceed to describe and claim.

Of the accompanying drawings, forming a part of this specification, Figure 1 represents a side elevation of a watch screw-driver embodying my invention. Fig. 2 represents an enlarged sectional view of a portion of the same. Fig. 3 represents a side view of a part of the handle or body portion of the screw-driver. Fig. 4 represents a section on line 4-4 of Fig. 3. Fig. 5 represents a section on line 5-5 of Fig. 4. Figs. 6 and 7 represent sections on lines 6-6 and 7-7 of Fig. 5.

The same reference characters indicate the same parts in all the figures.

In the drawings, *a* represents the body or handle portion of a screw-driver, the same being in this embodiment of my invention formed in a single elongated substantially cylindrical piece of suitable metal, such as steel, the periphery of the said body being preferably longitudinally fluted to facilitate the grasping and rotation of the body by the thumb and finger of the operator. In one of the end portions of the body is formed a cylindrical socket or cavity *b* and a longitudinally-extending slot *c*, which is narrower than the diameter of the cavity

and extends above the bottom or inner end of the cavity, the said slot dividing the wall of the socket into two resilient jaws *b*² *b*², having semicylindrical inner faces adapted to grasp a cylindrical shank *d*. The portion of the slot that extends above the bottom of the socket subdivides the portion of the body immediately above the socket into two resilient supplemental jaws *b*³ *b*³, having flat faces formed by the sides of the slot, the said faces being adapted to bear on either of two flat-sided terminals *d*', formed on the end portions of the shank *d*.

The flat sides 8 of the terminals *d*' are inclined relatively to each other and to the axis of the shank *d* in such manner that each terminal is wedge-shaped, its thickness being gradually reduced from its inner to its outer portion. The thickness of the inner portion of each terminal is somewhat greater than the width of the slot *c*, so that when the shank is inserted in the cavity *c* the terminal *d*' at its inner end will partially enter the space between the supplemental jaws *b*³ above the socket, the base portion of the terminal being wedged between the supplemental jaws and prevented from further inward movement before the upper portion of the terminal can reach the bottom or inner end of the slot *c*.

The portion of the body *a* containing the jaws *b*² and *b*³ is externally tapered and is provided with means for pressing the said jaws simultaneously against the cylindrical portion of the shank *d* and the sides of the terminal *d*'. As here shown, this result is effected by a collar *e*, adapted to slide on the tapered portion of the body and having a frictional engagement therewith, said collar being formed so that when moved upwardly on the tapered portion of the body it will exert inward pressure on the said jaws.

Before inserting a shank *d* in the socket the collar *e* is removed or loosened, and the shank is then inserted, the inner terminal *d*' entering and being wedged between the supplemental jaws *d*'. The collar *e* is then forced upwardly until the jaws *b*² are pressed firmly against the cylindrical portion of the shank and the jaws *b*³ against the sides of the terminal *d*'. It will be seen that the shank is 100

grasped simultaneously by two pairs of jaws and is therefore adapted to be very firmly and securely engaged with the body or handle portion and quickly released and removed.

5 The cylindrical socket *b* may be readily and economically formed by drilling an orifice in the body *a*, the cylindrical form of the socket enabling it to engage a cylindrical shank *d*. The said shank may also be economically 10 made by cutting a cylindrical metal rod into sections and flattening the end portions to form the terminals *d'*.

I claim—

15 A screw-driver comprising, first, a body having an externally-tapered end portion containing a socket-cavity and a longitudinal slot narrower than the cavity and extending through the wall and above the bottom of the latter, the said slot subdividing the wall of 20 the cavity into resilient jaws having inner faces formed to grasp a shank, the slot also

subdividing the portion of the body immediately above the cavity into supplemental jaws formed to engage a terminal on said shank; secondly, means for forcing said jaws inwardly 25 to close them simultaneously upon said shank and terminal, and, thirdly, a cylindrical shank formed to be removably inserted in the socket and having flattened inclined sides at its end portions forming wedge-shaped terminals, 30 either of which is formed to enter the slot between the supplemental jaws, each terminal being thicker at its base portion than the width of the slot, so that the base of the terminal is wedged in the slot.

35 In testimony whereof I have affixed my signature in presence of two witnesses.

OLOF OHLSON.
